UNITED STATES PATENT OFFICE.

WILLIAM H. TOWERS, OF NEW YORK, N. Y., ASSIGNOR TO W. S. BARD, OF SAME PLACE.

IMPROVEMENT IN BROOM-HANDLES.

Specification forming part of Letters Patent No. **33,502**, dated October 15, 1861.

To all whom it may concern:

Be it known that I, WILLIAM H. TOWERS, of the city, county, and State of New York, have invented a new and useful Improvement in Broom-Handles; and I do hereby declare that the following is a full, clear, and exact description of the same, reference being had to the accompanying drawing, making part of this specification.

The figure is a side elevation of the improved broom-handle with the broom-corn secured thereto.

This invention although very simple, is nevertheless very useful in facilitating and strengthening the attachment of the broom-corn to the broom-handle; and it consists in the formation of a series of circular grooves in the handle of such relative sizes and at such relative distances apart as shall correspond with the sizes and positions, respectively, of the series of surrounding layers of broom-corn and windings of wire around them.

For example, the lower groove 1 is formed in the handle A, opposite where the first series of windings of wire around the end of the first layer of broom-corn a takes place, and is made of sufficient capacity to enable the wire in winding to press this first layer of broom-corn, which is equally spread around the handle tightly, into the said groove 1. The next groove 2 above is formed opposite where the series of windings of wire is to be wound around the ends of bodies of broom-corn b, bunched against the sides of the handle opposite each other, and is the same in size as

the first groove 1. The next groove 3, which is somewhat smaller than the grooves 1 2, is formed opposite where the series of windings of wire which is to secure the end of the next layer c of broom-corn, which, like the first layer a, is equally distributed around the handle. The next groove 4, which is a slight degree still smaller, is formed opposite the windings of wire which secure the end of the next layer d of broom-corn, and the next groove 5 opposite the windings of wire which secure the end of the next and final layer e of broom-corn. By such relative distances apart and sizes of the grooves 1 2 3 4 5 their capacities and positions are made to correspond, respectively, with the sizes of the series of layers a b c d e of broom-corn designed to be bound in them and the positions of the series of windings of wire employed for that purpose, thus insuring an extraordinary degree of firmness of attachment of the broom-corn to the handle with less wire than heretofore employed.

What I claim as new, and desire to secure by Letters Patent, is—

Forming a series of grooves around broom-handles of such relative sizes and distances apart as shall correspond with the bulk of the successive layers of broom-corn, and the positions of the respective series of windings of the wire binding the ends of the same in the grooves, substantially as described.

WM. H. TOWERS.
